UNITED STATES PATENT OFFICE.

EVAN WILLIAMS, OF NEW CASTLE, PENNSYLVANIA.

ROLL FOR ROLLING-MILLS.

No. 907,930.

Specification of Letters Patent. Patented Dec. 29, 1908.

Application filed May 7, 1907. Serial No. 372,378.

To all whom it may concern:

Be it known that I, EVAN WILLIAMS, a citizen of the United States of America, residing at New Castle, in the county of Lawrence and State of Pennsylvania, have invented 5 certain new and useful Improvements in Rolls for Rolling-Mills, of which the following is a specification, reference being had therein to the accompanying drawing.

10 This invention relates to rolls for rolling mills, and the invention has for its object to provide a roll that will permit of sheets being rolled in a cooler state.

Another object of this invention is to provide 15 a strong and durable roll which will not break and cause delay.

With the above and other objects in view, the invention consists in the novel construction, combination and arrangement of parts 20 to be hereinafter more fully described and then specifically pointed out in the appended claim.

Referring to the drawing forming part of this specification, like numerals of reference 25 designate corresponding parts throughout the several views, in which:

Figure 1 is an elevation of a roll partly in section, Fig. 2 is an elevation of the shaft or core thereof, Fig. 3 is a cross sectional view 30 of the roll.

To put my invention into practice, I construct a roll having a cast iron body 1, a steel shaft or core 2 having necks 3 and wabblers 4. The shaft or core 2 between the 35 shoulders 5 of the necks 3 is longitudinally corrugated or fluted, as at 6, whereby the cast iron body or shell of the roll will take a

firm grip upon the shaft or core 2 at every point and cannot be easily broken when cast upon the hard and durable shaft or core of 40 the roll. Should the body 1 of the roll be damaged or injured, it can be removed and another body cast upon the shaft or core 2.

It will be apparent from the illustration of my invention that I have devised a strong 45 and durable roll which will facilitate the operation of rolling.

Such variations in the size and minor details of construction, as are permissible by the appended claim, may be resorted to 50 without departing from the spirit and scope of the invention.

What I claim and desire to secure by Letters Patent, is:—

A roll comprising a steel core having necks 55 adjacent each end of greater diameter than the body of the core, a body cast on the core and having its ends abutting said necks, equally spaced longitudinally extending flutes arranged on the periphery of said core 60 and terminating at the necks of the core, the said flutes being substantially V-shaped, in cross section to form V-shaped grooves between the flutes to receive the material of which the body portion is formed while the 65 flutes project into said material whereby the body grips the core at all points throughout the periphery of the latter.

In testimony whereof I affix my signature in the presence of two witnesses.

EVAN WILLIAMS.
